UNITED STATES PATENT OFFICE.

SETON J. ALLEN, OF VINELAND, NEW JERSEY.

SHOE.

Application filed December 20, 1926. Serial No. 155,843.

This invention relates to shoes, and more particularly to that type of shoe in which an arch supporter is combined with the structure of the shoe and forms a permanent part thereof, as distinguished from those structures in which the arch supporter is an entirely independent member, which can be placed within the shoe, or which can be placed beneath the insole of the shoe 5 and removed therefrom, as occasion may require, for the purposes of furnishing the necessary support to the arch of the foot.

Heretofore, it has been extremely difficult, if not impossible, to manufacture by machine shoes of the type described herein in quantity production, due to the thickening of that portion of the shoe which lies immediately under the arch of the foot, and if manufactured by machine, the operation on 10 that portion of the shoe lying directly beneath the arch is so difficult and intricate as to make the operation extremely costly. It is for this reason that shoes embodying permanent arch supporting surfaces therein 15 have been almost uniformly manufactured by hand.

Furthermore, while the manufacture of shoes having permanent arch supporting surfaces therein is known in the art, I am 20 not aware of any shoe in which this arch supporting surface is so molded or formed both with reference to the longitudinal extent as well as the transverse disposition of the arch supporting surface, that it 25 conforms exactly and precisely to the bony structure of the human foot, and to this end the bony structure of the anatomy of the human foot is briefly described, so that the present invention may be more readily 30 understood.

The foot is composed of a multiplicity of relatively small bones comprising the ankle bone, the heel, the tarsus, the metatarsal bones, the phalanges, and other bony structures. An examination of this bony structure shows that an arch is produced not only longitudinally of the foot but also transversely. This is due to the fact that the metatarsal bone of the big toe is much 45 larger in diameter than the metatarsal bones of the other toes, and that these metatarsal bones of the second, third, fourth and fifth toes are arranged in step formation, so that the metatarsal bones of the smallest toe and 50 the metatarsal bone of the big toe are the

only bones that are supported in direct contact with the shoe, except for the interposition of a relatively thin layer of the fleshy portion of the foot. It is necessary, therefore, that the second, third, and fourth metatarsal bones be given additional support in case of fallen arches or other weakness of these bones. At the same time, the tarsal bones are likewise so arranged that a transverse recess is formed thereby. 60

It is an object of the present invention to so form the arch supporting surface in the shoe that it will conform to and support both the tarsal and metatarsal bones of the foot longitudinally and transversely thereof, 65 and at the same time to conform to this recess formed by the arrangement of the bones of the foot, so that all danger of collapse of the bones supported by the arch supporter is eliminated. Further, in cases 70 where the bones have already fallen or are so weak as to need support, the present invention is intended to maintain these bones 75 of the foot in proper position.

In carrying out this invention, I make use 80 of a last with a concave or recessed portion in the lower surface thereof and apply thereto an insole which has been moistened, and mold this insole while in its moistened condition to conform to the recess in the 85 last. The particular last employed, however, is the subject matter of a separate application, and need not be described herein, it being thought to be sufficient to give a 90 general outline of the operations employed so that a clear understanding of the present invention may be had.

Referring to the accompanying drawings 95 forming part hereof and in which corresponding numbers refer to similar parts,

Figure 1 is a plan view of the shoe with the upper and heel thereof broken away so as to more clearly illustrate the positioning and configuration of the arch supporting surface; 100

Fig. 2 is a bottom view of the insole employed in my shoe and illustrating the application thereto of a patch;

Fig. 3 is a transverse sectional view taken on or about the line 3-3 of Figure 1; 105

Fig. 4 is a longitudinal sectional view;

Fig. 5 is a bottom plan view of the insole with portions broken away so as to show the application of the patch and shank thereto; 110

Fig. 6 is a view showing the insole patch and shank in disassembled relation and in the order of application to the insole.

Fig. 7 is a cross sectional view of the inner sole of a shoe taken on line 7—7 of Fig. 4 and Fig. 5 showing the elevation of the inner face of the insole at that section, A being the outer side of the shoe.

Fig. 8 is a cross sectional view of the inner sole of a shoe taken on line 8—8 of Fig. 4 and Fig. 5 showing the elevation of the inner face of the insole at that section.

Fig. 9 is a cross sectional view of the inner sole of a shoe taken on line 9—9 of Fig. 4 and Fig. 5 showing the elevation of the inner face of the insole at that section, and indicating the angular disposition of this elevation at that section, in reference to a given plane.

Fig. 10 is a cross sectional view of the inner sole of a shoe taken on line 10—10 of Fig. 4 and Fig. 5 showing the elevation of the inner face of the insole at that section, and indicating the angular disposition of this elevation at that section, in reference to a given plane.

Fig. 11 is a cross sectional view of the inner sole of a shoe taken on line 11—11 of Fig. 4 and Fig. 5 showing the elevation of the inner face of the insole at that section, and indicating the angular disposition of this elevation at that section, in reference to a given plane.

Fig. 12 is a cross section view of the inner sole of a shoe taken on line 12—12 of Fig. 4 and Fig. 5 showing the formation of the insole at that section and indicating the fact that on that section line it is substantially parallel to a given plane surface and approximately flat or level.

Referring more particularly to the drawings, I have shown a shoe of the conventional type, with the exception of the structure immediately beneath the arch of the foot and comprising an outer sole 1 of usual construction, and 2 represents the shoe upper secured to the outer sole in any suitable fashion. In order to support the arch of the foot I have provided an insole 3 of the channel type wherein the channels 4 extend completely around the sole and form means by which the upper is secured thereto. It is the usual practice to form these channels so that the edges of the upper can be sewed or otherwise secured thereto, and after this operation is completed, the outer sole is fastened to the inner sole by means of stitching, tacks or any other suitable securing members. This insole is provided with a raised arch supporting surface 5 extending longitudinally of the shoe, from a point slightly to the rear of the heel breast forwardly to a point approximately corresponding with the position of the ball of the foot when placed in the shoe. In other words, this

supporting surface extends throughout the length of the arch formed by the tarsal and metatarsal bones, and terminates at one end near the heel portion of the foot and at its other end directly beneath the joint which connects the metatarsal bones with the phalanges. In this manner, a longitudinal support for the foot is provided, and at the same time necessary transverse support for the tarsal and metatarsal bones of the foot is formed, due to the fact that the supporting surface on its lower side is concaved by being molded into the last and is given the configuration substantially as shown in the drawings, and in which this supporting surface 5 is shown as extending partially across the insole transversely thereof, and accordingly it extends substantially across the transverse arch formed by the bony structure of the foot.

Reference to Fig. 3 of the drawings indicates the insole 3 provided with the flange 4 and the raised supporting surface 5, and in this view is illustrated the particular configuration of the supporting surface. It is to be seen that the forward portion 6 of the raised supporting surface 5 has an angle of inclination substantially the same as that of the outer sole or substantially parallel to the outer sole, but that the rear portion 7 of the supporting surface 5 has a greater angle of inclination, which in effect imparts a twisted formation to the raised supporting surface 5, the greatest angle of inclination and the greatest convexity of said arch supporting surface is at the intermediate portion thereof.

It has been found in actual practice that the transverse arch formed by the bones of the foot is not constant from the forward edge of the metatarsal bones back to the ankle bone, but that the arch formed by the metatarsal bones has one angle of inclination while the arch formed by the tarsal bones has an inclination at a slightly greater angle. Accordingly, in order to properly support the foot by a construction which corresponds in minute detail to the bony structure of the foot, I have provided the raised supporting surface 5, as shown herein, with the peculiar formation above described, which is believed to be absolutely essential to the proper supporting of the bones of the foot. Furthermore, the particular construction of the arch supporting surface as shown, clearly furnishes an exact fit with the arch of the foot at the inside thereof. It is believed, therefore, that the construction as set forth herein is essential to the proper supporting of the foot, although it is known that arch supports have been produced which are said to conform to the bony structure of the human foot.

The insole, having been placed upon the last in a moistened condition, and having

had the arch supporting portion 5 molded therein so as to give the configuration shown in Fig. 3, has applied thereto a patch 8, which is of substantially the same configuration as the concaved lower side of the supporting member 5, as clearly illustrated in Figs. 2 and 4. It is to be noted that this patch 8 is of such proportions that it is confined between the channels 4 on the sole and that it in no way interferes with the channeling operation of the insole, nor with the sewing of the shoe upper thereto.

I am aware of the fact that patches, so called, have been used for some time, and 15 am not attempting to appropriate the idea broadly of using a patch, but I believe myself to be the first to use a patch of the configuration set forth herein, and which is so proportioned that it is confined between 20 the channels 4. By so proportioning this patch 8 that it in no way interferes with the channeling and sewing operations, I have succeeded in producing a structure which can be made entirely by machinery, 25 and which reduces the difficulty now experienced in sewing these channels to the upper of the shoe, due to the fact that the patch lies entirely within the channels. It is thought that it will be readily understood 30 that by confining this patch 8 within the channels 4, the shoe can be operated upon by machinery with the same facility as if the patch 8 were not present, and in the same manner in which the ordinary shoe 35 is now manufactured without arch supporting structures therein.

I have provided a structure, therefore, which is believed to answer all of the necessities of an arch support and at the same 40 time have constructed a shoe which can be built in quantity production and by machinery with ease and facility, and without increasing the cost of manufacture to any considerable extent, due to the fact that the 45 stiffening or increase in thickness of that portion of the shoe lying immediately below the arch of the foot in no way obstructs or interferes with the ordinary machine methods now employed in shoe manufac- 50 ture.

The patch 8 is provided with a narrow rear portion 8^a which gradually diminishes in width, intermediate its ends, and at its forward end 8^b flares outwardly to a width 55 greater than the rear portion 8^a, so that the broader forward end of the patch extends completely across the transverse arch of the foot formed by the metatarsal bones, and it is to be further understood that the rear 60 end 8^a of the patch is comparatively thin but gradually merges into a thickened forward end, as clearly shown in Fig. 4. This formation maintains the arch supporting portion 5 at its proper height at the forward 65 end.

After the application of the patch to the concave lower face of the arch supporting surface 5 I then secure to the insole a shank 9 comprising a relatively stiff member, which may be made of leather or other suitable 70 material, which is suitably reinforced or stiffened by means of a metal strip 10 extending longitudinally thereof and projecting from the heel end to a slight degree and secured to the leather member in any suitable manner. This shank member 9 is so placed upon the patch 8 that the metal reinforcing member 10 lies between the shank 9 and the patch 8, thereby rigidly maintaining and supporting both the patch and the 80 arch supporting portion 5 so that it is permanently maintained in its proper elevation and curvature.

After the application of the shank to the insole, that portion of the shoe from the 85 forward end of the shank to the toe of the shoe is filled with a suitable composition filler 11, which is well known in the art and need not be described in detail, and the outer sole is then applied and secured to the upper 90 and insole in any suitable manner.

It is to be noted that in the present construction that portion of the shoe immediately below the arch of the foot consists of a laminated structure, comprising the 95 outer sole, the shank, the patch, and the insole provided with the particularly shaped arch supporting portion, and that the filler 11 terminates adjacent the forward end of this laminated structure and in no way 100 enters into the construction of the arch supporting portion of the shoe. This is of importance, due to the fact that by using the filler in this portion of the shoe immediately beneath the arch of the foot a 105 rigid supporting surface for the arch could not be secured. In the present instance, however, the laminations constituting this arch supporting portion are all rigid in construction and form a solid permanent structure, which is highly desirable in shoes of 110 the type described herein.

The patch 8 may be secured to the insole in any suitable manner, either by means of cement, tacks, or other securing devices, and 115 the same is true of the shank 9. The securing of these elements, however, forms no part of the invention, and it is believed to be immaterial what particular fastening means are employed.

From the foregoing, it will be seen that I have provided a shoe which has an arch supporting surface similar in construction and configuration to the bony structure of the foot, and by providing the supporting 125 surface 5 with a greater angle of inclination transversely at the intermediate section thereof than at the forward end, I provide a structure that will support the metatarsal bones at the correct or normal angle of in- 130

clination, and also support the tarsal bones at their normal angle of inclination, which is slightly greater than the angle of inclination of the metatarsal bones.

- 6 Furthermore, it will be seen that I provide a shoe that can be easily and readily manufactured by means of shoe machinery which is in common use to-day, and that the cost of the manufacturing is materially reduced
- 10 owing to the fact that it is unnecessary to channel the patch 8 since this patch lies or is confined between the channels and in this manner does not interfere with the channeling or sewing operations required
- 15 to complete the shoe.

It is to be understood that the arch supporting portion 5 of the insole can be formed in any suitable manner, by means of a last provided with a concave or hollowed bottom surface upon which the insole is placed when moistened, and I desire it to be understood that this arch supporting surface may be formed by the molding of the insole by itself, or that the insole may be placed

- 20 upon the last and the patch applied to the insole and the insole and patch both forced into the concave lower surface of the last, to give the insole the raised supporting surface of the configuration described herein.
- 25 It is to be understood that the formation of the arch supporting surface which I provide in my shoe is such that it has a slightly convexed elevation above the inner surface of the inner sole at its forward end and a
- 30 more sharply convexed and more elevated formation at its intermediate section while near its rear end it is of a slighter convexity and elevation than at its front end or intermediate section and which rear end sub-
- 35 stantially merges with the level of the heel formation of the inner sole. It is also to be understood that the area and shape of the arch supporting surface as formed in my shoe is such that on the outer side of the
- 40 inner sole or outer side of the shoe which would correspond to the outer side of the foot, it forms a marginal section which is substantially at a level of the unelevated section of the inner surface of the inner sole,
- 45 which section bounds and determines the shape and extent of the elevated arch supporting surface on that side of the foot or

inner sole. The position and extent of this marginal section will be seen from Fig. 3.

While I have illustrated the patch as applied to an insole of the channel type, I desire it to be understood that I do not limit myself to this particular type of insole, but can employ the same structure as shown herein in connection with channeled or any other type of insole, and I further desire to be understood as not limiting myself to any details of construction, but may modify the structure set forth herein within the scope of the claims hereunto appended.

I claim:

1. In a shoe, an inner sole provided with a convexly elevated and twisted section arranged therein to fit the metatarsal and longitudinal arches of the foot, a yielding patch 70 filler attached to the lower side of said inner sole, disposed in and substantially conforming to said convexly elevated twisted section, throughout substantially the entire area thereof, reinforcing said convexly elevated 75 twisted section, and holding said section in formed shape, and a resilient shank, secured to said patch and inner sole, supporting said patch and inner sole in formed shape.

2. In a shoe, an inner sole provided with a convexly elevated and twisted section, arranged therein to fit the metatarsal and longitudinal arches of the foot, said section extending from the ball of the foot substantially to the heel thereof, said section having a slightly convexed elevation above the inner surface of the inner sole at its forward end, with a more sharply convexed and more elevated intermediate section, and which near its rear end is of a slighter convexity and elevation than at its front end or intermediate section, and at which rear end substantially merges with the level of the heel formation of the inner sole, the twist of said elevated section being such that it is higher 90 for substantially its entire length on the inner side of the foot portion of the inner sole than on the outer side of the foot portion of the inner sole and which merges with said inner side formation.

In testimony whereof I have hereunto set my hand.

SETON J. ALLEN.
